NONREFILLABLE BOTTLE

Frank R. Lueck, Wauwatawa, Wis.

Application February 18, 1937, Serial No. 126,318

4 Claims. (Cl. 215—22)

This invention relates to nonrefillable bottles.

An object of the present invention is to provide a simple, inexpensive, yet highly effective, attachment which may be readily applied to bottles and the like to render the same substantially proof against refilling.

Another object is to provide an improved attachment for bottles capable of rendering the bottle substantially proof against refilling without interfering with adequate discharge of liquid therefrom.

Another object is to provide a nonrefillable attachment for bottles which will regulate and control the discharge from the bottle in a manner to facilitate pouring.

Another object is to provide a nonrefillable attachment for bottles which shall be proof against undetectable tampering.

Other more specific objects and advantages will appear, expressed or implied, from the following description of an illustrative embodiment of the present invention.

In the accompanying drawing—

Figure 1 is an axial sectional view on an enlarged scale of a nonrefillable attachment constructed in accordance with the present invention and shown applied to the neck of a conventional bottle.

Fig. 2 is a transverse sectional view.

Fig. 3 is a view similar to Fig. 1 showing the position of parts when the bottle is tilted into position for pouring.

The attachment selected for illustration comprises a substantially cylindrical housing 10, adapted for insertion into the neck 11 of a bottle, and closed at its lower end except for a port 12 formed in the center of the substantially flat bottom 13 thereof. The upper end of the housing is enlarged to form an offset annular shoulder 14 by which it is supported, the shoulder carrying an upstanding peripheral flange 15.

The port 12 is normally closed by an appropriate valve 16 which normally seats upon the bottom 13 of the housing. For purposes which will hereinafter appear, the valve 16 is of light weight to render it buoyant in the type of liquid normally contained in the bottle. In this instance the valve comprises a piece of cork preferably of cylindrical form having its flat top and cylindrical side surfaces covered by a thin-walled cartridge 17, preferably of metal, tightly fitted thereover. The exposed lower face 18 of the cork is ideally suited to seal the port 12 by coaction with the flat seat 13, while the metallic cartridge 17 provides smooth, hard, wear-resist-

ing surfaces ideally suited to coact with guide ribs 19 and with a counterweight or ball 20 hereinafter again referred to.

The ribs 19 are preferably shaped so that each presents a narrow, smooth, vertically extended surface to the valve 16 and they are so spaced that they together form a loosely fitting guideway for directing the valve toward and from its seat. The guides 19 are preferably stamped in the walls of the housing 10 and are preferably spaced from the valve seat 13 so as to provide a clear space extending continuously about the valve and its seat.

The valve 16 is forcibly retained against its seat 13 by gravity and particularly by a heavy member, such as a ball 20 preferably of non-magnetic material, which normally rests against the top flat surface of the valve substantially at its center. An appropriate ball retainer is provided which functions to limit lateral displacement of the ball 20 so as to keep the ball spaced from the housing walls and near the center of the valve 16 in all positions of the bottle, and which also functions to maintain a closing pressure of the ball against the valve except when the bottle is tilted through a predetermined angle beyond the horizontal into pouring position, in which position the ball is permitted to retract by gravity in a direction to permit the valve to open.

Although a ball retainer capable of functioning in the manner described may assume various forms, that shown comprises a sheet metal disk 21, disposed to span the housing above and adjacent the ball, and fashioned to provide a central shallow pocket or recess 22 into which the ball 20 projects in all positions of the bottle. The continuous rim 23 of the recess serves to limit lateral displacement of the ball and, when the bottle is tilted, provides a shoulder or fulcrum on which the ball is free to rock out of or into pressure contact with the valve when the bottle is tilted into or out of pouring position.

In order to insure prompt and proper action of the ball 20 under all conditions, movement of the ball into the recess 22 is limited so that the center of gravity of the ball is maintained between the plane of the rim or fulcrum 23 and the valve 16. Although this limiting position may be determined by the size or diameter of the rim 23, the back 24 of the recess performs that function in the device shown, the diameter of the rim 23 being preferably such as to clear the ball slightly when the latter is seated against the back wall 24, thereby to avoid a seal between

the ball and rim and thus avoid any tendency of the ball to stick in the recess.

In this instance the disk 21 is supported by a down-turned peripheral flange 25 which rests upon the shoulder 14 and which is centered by the flange 15. The disk 21 is preferably dished, as indicated, and provided with a peripheral series of openings 26 disposed adjacent the flange 25 directly over the shoulder 14.

10 The disk 21 is covered by an appropriate hood which constitutes in effect a continuation of the housing 10. The hood shown comprises a cylindrical portion 27 surrounding the housing flange 15, a shoulder 28 for positioning and retaining the disk 21 and its flange 25, and an inwardly tapered or arched portion 29 which terminates in a central flanged outlet or pouring spout 30. The housing flange 15 is tightly fitted in the hood portion 27 so as to retain the parts in assembled 15 relation and thereby provide an assembly which may be applied, as to unit, to the bottle neck.

It will be noted that the disposition of the holes 26 adjacent the flange 25 provides a ready outlet for liquid from the bottle, permitting the liquid 25 to follow a natural course along the sides of the housing 10 and hood, free from damming or other restraint. The fact, however, that the holes 26 are disposed laterally from the spout 30 and directly above the shoulder 14 renders it rather 30 impossible to project a wire or other tool through the holes 26 and past the shoulder 14 into position for tampering with the valve 16.

As an additional precautionary measure against tampering an additional shield 31 may be interposed between the ball retainer and hood. The shield shown comprises a woven wire screen having its marginal portion 32 anchored by and between the shoulder 28 and the flange 15 and having its central portion arched to accommodate 40 the ball retainer. It has been found that a thirty mesh screen, mounted in the manner described, provides an effective barrier against tampering and at the same time permits liquid from the bottle to discharge freely therethrough, if vented 45 to admit air to the bottle. In this instance, vent holes 33 are formed in the screen, preferably spaced inwardly from the holes 26, and internal ribs 34 formed in the hood insure spacing of the screen therefrom so as to assure adequate venting.

The unit may be permanently affixed to the bottle 11 in various ways but, in this instance, the hood is provided with a depending flange or skirt 35 adapted for external application over 55 and about the neck of the bottle and adapted to be permanently interlocked with the neck by spinning or rolling the same into an appropriate rib-and-groove formation 36 on the neck. By this method of attachment, removal of the unit 60 is very difficult, and removal and replacement without detection is virtually impossible. The unit is applied of course after the bottle is filled.

Any appropriate gasket 37 or gasket material 65 may be employed to seal the joint between the unit and bottle, and the bottle may be closed by a cork or the like placed in the spout 30.

The device shown and described not only renders the bottle proof against non-detectable 70 refilling, but it also serves to facilitate pouring. It will be noted that, as the bottle is tilted, for 75 purposes of pouring, from the upright position of Fig. 1 through a horizontal position and toward the inclined position of Fig. 3, the valve 16 is retained closed by the weight of the ball 20. Throughout this range of angular positions

of the bottle, the ball 20 remains in the dotted line position of Fig. 3, resting upon its fulcrum 23 which its center of gravity between the fulcrum and valve 16, so that its weight maintains a closing pressure on the valve. 5

This condition maintains until the bottle is so tilted as to cause the center of gravity of the ball 20, contained in the axis x-x, to pass beyond the vertical plane of the line y-y passing through the fulcrum 23, and when that occurs 10 the ball rocks into the recess 22 in a direction away from the valve 16 so as to permit the valve to open. Discharge from the bottle is thus prevented until the bottle has been tilted into a position convenient for pouring, and when pouring 15 does occur it is not excessive, because the rate of discharge is governed by the extent to which the valve has opened and, in this instance, the ball 20 limits the opening movement. It will also be noted that when the bottle is re-20 turned from pouring position toward a horizontal position, the center of gravity of the ball passes back through the vertical plane y-y, whereupon the ball rocks on its fulcrum 23 in a direction to again promptly close the valve and thereby surely and promptly cut off discharge from the bottle. Objectionable after-flow following actual pouring is thus prevented.

It will also be noted that since the ball 20 is maintained in a substantially central position 30 relative to the valve 16, and since the coacting top surface of the valve is substantially flat, the closing pressure exerted by the ball against the valve is in a direction parallel to and adjacent the central axis of the valve, so that there is no 35 tendency for the valve to rock or cant in its guideway.

It will also be noted that since, as above pointed out, the valve 16 is retained in closed position by the ball 20 in all angular positions 40 of the bottle throughout that range between the upright position of Fig. 1 and the downwardly inclined position of Fig. 3, it is impossible for liquid, under pressure or otherwise to enter the bottle in any of those positions. Furthermore, 45 in the tilted position of Fig. 3 and in all angular or inverted positions of the bottle beyond that range, any body of liquid forced upwardly into the housing 10 from the outside will act upon the buoyant valve 16 to promptly lift the same 50 into closing position and thereby prevent entry of such liquid into the bottle. The bottle is proof against refilling.

It will also be noted that the hood 29, the 55 shield or screen 31, the position of the holes 26 and 33, and the shoulder 14 combine to render the device substantially tamper proof. In this connection it will be noted that the shield or screen 31 is visible through the outlet 30 so that any mutilation thereof in an effort to gain access 60 to the holes 26 in the disk 21 may be readily detected.

Various changes may be made in the embodiment of the invention hereinabove specifically 65 described without departing from or sacrificing the advantages of the invention as defined in the appended claims.

I claim:

1. A nonrefillable attachment for bottles comprising a ported housing having a peripheral shoulder, a buoyant valve moveable in said housing below said shoulder for controlling passage of liquid therethrough, a relatively heavy ball normally resting on said valve, a member spanning said housing and coacting with said ball to 75

5 maintain a closing pressure on said valve except when the bottle is tilted substantially beyond a horizontal position, said member having a peripheral series of openings disposed directly over said shoulder, and means spaced above and covering said openings and forming an outlet spaced inwardly from said openings.

2. A nonrefillable attachment for bottles comprising a housing having a port at its lower end and an outlet at its upper end, said housing also having an enlarged portion forming a shoulder intermediate its ends, a member spanning the enlarged portion of said housing and having a peripheral series of openings disposed directly above said shoulder, valve means disposed below said member and cooperating with said port to control passage of liquid through said housing, and means spaced above and covering said openings.

10 3. A nonrefillable attachment for bottles comprising a housing having a port at its lower

end and an outlet at its upper end, said housing also having an enlarged portion forming a shoulder intermediate its ends, a member spanning the enlarged portion of said housing and having a peripheral series of openings disposed directly above said shoulder, a woven wire screen spanning said housing adjacent said member, and valve means below said member cooperating with said port to control passage of liquid through said housing.

15 4. A nonrefillable attachment for bottles comprising a housing having a port at its lower end and an outlet at its upper end, a woven wire screen spanning said housing intermediate the ends thereof and vented to admit air through said housing when said screen is clogged by liquid, and valve means below said screen and cooperating with said port to control passage of liquid through said housing.
